CLUTCH MECHANISM

Kenly C. Bugg, Fort Wayne, Ind., assignor to
Neptune Meter Company, a corporation of New
Jersey

Original application August 16, 1939, Serial No.
290,402. Divided and this application January
27, 1942, Serial No. 428,345

5 Claims. (Cl. 192—66)

This application is a division of my copending application Serial No. 290,402, filed August 16, 1939, now Patent No. 2,298,343, dated October 13, 1942.

The present invention relates to clutches and more particularly to a clutch mechanism particularly useful in apparatus such as, for example, resetting mechanism for counting devices where it is desirable to provide a connection between the drive shaft and the counters for counting purposes and to hold the drive shaft stationary while the counting devices are reset to zero.

One of the objects of the invention is to provide a clutch mechanism capable of effecting a driving connection between two elements and operable to release one of the elements for independent movement and to hold the other of the elements against movement.

Another object of the invention is to provide a clutch mechanism which is relatively simple, sturdy and easy to operate.

The above and additional objects of the invention will become apparent upon consideration of the following detailed description and the appended claims when read in connection with the accompanying drawings, in which

Fig. 1 is a view in vertical elevation on a reduced scale of the driving and resetting mechanism for the counters of a computing device illustrating one of the many applications of the clutch mechanism of this invention, the position shown being that of providing a connection between the drive and the counters;

Fig. 2 is a fragmentary view in vertical elevation of the driving and resetting mechanism in a pullback position;

Fig. 3 is a fragmentary view in elevation showing the clutch mechanism in a position releasing the counters and holding the drive;

Fig. 4 is a fragmentary view in side elevation of the driving and resetting mechanism near the end of a resetting operation with the clutch mechanism in counter connecting position;

Fig. 5 is a sectional view taken on line 10—10 of Fig. 2 to show the details of the clutch connection and brake device; and

Fig. 6 is a view in side elevation of the means for controlling the cyclic operation of the reset mechanism.

Referring to Fig. 1 of the drawings, a computer head is shown for purposes of illustrating the present invention embodying a plurality of counters adapted to indicate the amount and cost of a substance or units being counted. For ex-

ample, the computer head comprises a supporting frame 10 upon which are mounted counter units 12 and 12a, 13 and 13a and a driving and resetting mechanism 14. The upper counter units 12 and 12a are provided with appropriate characters in the order of units, tens and hundreds representing the cost of the substance being counted, while the lower counter units 13 and 13a are provided with appropriate characters in the same order representing the amount, such as volume, length, number, etc., depending upon the character of the substance being counted. Disposed between the four counter units is a resetting mechanism which is adapted to reset all four counters simultaneously, the resetting mechanism being provided with a form of clutch mechanism constructed in accordance with my invention.

Since the counters form no part of the present invention it is only necessary for the purpose of illustrating the present invention to understand that the counters are of the type capable to perform a counting operation when the shaft thereof is rotated in one direction and to be reset to zero when the shaft is rotated in a reverse direction.

Referring to Fig. 1 of the drawings, it will be noted that the shaft 18 of each counter unit is mounted at right angles to the frame 10 of the computing device. The corresponding counters 12, 12a and 13, 13a are interconnected for corresponding movement by shafts 62 and 63, mounted in bearings 64 and 65, respectively.

Referring to the upper counter units 12 and 12a the shaft 62 intersects at right angles the center line of the shafts 18 of the counter units. Bevel gears 66 and 67 are provided on the shaft 62 to mesh with bevel gears 68 and 69a of counters 12 and 12a, respectively. The lower shaft 63 is provided with a similar bevel gear connection for transmission of motion to counters 13 and 13a.

The upper and lower counter units are driven independently of each other by separate drive shafts as shown more particularly in Patent No. 2,298,343. Where the computer is used in connection with a dispensing pump including a metering device, the lower or volume indicating counters 13 and 13a are adapted to be driven directly from the metering device. The upper counters which are adapted to indicate the cost of the liquid being dispensed are driven from the metering device through a price variator mechanism (not shown) whereby the cost indications may be correlated with respect to the price indicated by the price variator mechanism.

A clutch shaft 72 is driven from the drive shaft that is connected to the price variator mechanism. The driving movement is transmitted from the clutch shaft 72 to the upper counter units through a clutch gear 75, an idler gear 76 and a gear device 80. The gear device 80 of counter 12 includes the bevel gear 68 and a spur gear 82. The gear 82 meshes with the idler gear 76 whereby movement in a counting direction is transmitted to the shaft 18 of counter 12 and to the corresponding shaft of counter 12a by transmission through bevel gears 68 and 66, the shaft 62 and bevel gears 67 and 68a. The drive during a counting operation to the lower counters 13 and 13a from a clutch shaft 84 is identical with that described in connection with counters 12 and 12a, the clutch shaft 84 being driven by a drive shaft that is connected to the meter.

For the purpose of simultaneously resetting the several counters, a reset shaft 85 is shown in Fig. 1 rotatably mounted in the frame 10 with couplings 86 extending outwardly of the frame for engagement with a manually actuatable handle. The reset shaft is provided with a gear 88 which meshes with an idler gear 89 (Figs. 1 and 2). Interposed between the idler gear 89 and the gear device 80a of counter unit 12a is a gear 90 to which is secured a mutilated gear 91. During a resetting operation the mutilated gear is adapted meshingly to engage the gear 82a of the gear device 80a whereby counters 12 and 12a are driven in a reverse direction toward zero position, the motion being transmitted to the counter 12 from counter 12a backward through bevel gears 68a, 67, the shaft 62 and bevel gears 66 and 68. The resetting drive to counter units 13 and 13a is identical with the drive to 12 and 12a just described.

The clutch device 92 and the brake device 110 of the clutch mechanism is shown in detail in Fig. 5. Keyed to the shaft 72 is a gear 93 which provides a friction surface 94 adapted to engage the clutch gear 75 which is rotatably mounted on the shaft 72. The shaft 72 is threaded at 95 to a point adjacent gear 75. A clutch block 96 is threadably mounted on the threaded portion 95 for rotary movement relative to shaft 72 in directions toward and away from the keyed gear 93 to grip and release the clutch gear 75. The clutch block 96 is biased for movement toward the gear 93 by a spring 97 coiled about the shaft 72 with one end connected to the block 96 at 98 and the other end to a disc 99 rotatively adjustable and secured to the shaft 72 against shoulder 101 by a nut 100. The actuation of the clutch block 96 is controlled by the resetting mechanism through an arm 102 which is rotatably mounted in an annular recess 103 formed in the block 96. The surface of the block 96 adjacent the arm 102 is provided with ratchet teeth 104. A pawl 105 pivotally mounted on the arm 102 and biased by a spring 106 (Fig. 2) to engage the ratchet teeth 104 is adapted to retract the block 96 and thereby release the gear 75 when the arm 102 is moved counterclockwise, as viewed in Fig. 1.

The brake device 110 is provided for the purpose of holding the drive shaft against movement during resetting operations. The device 110 includes a stationary shaft in the form of a double-headed bolt 112 rigidly secured to the frame 10 by a nut 113 in spaced parallel relation to shaft 72. A gear 114 is rotatably mounted on the bolt 112 in friction engaging relation

with the frame 10 and in mesh with the gear 93 which is secured for rotation with shaft 72. Threadably mounted on the bolt 112 is a brake block 116 similar to the clutch block 96. The brake block 116 is biased for rotary movement toward the gear 114 by a spring 117 to frictionally grip the gear 114 against the shaft 72, thereby holding the shaft 72 against movement. The brake block 116 is provided with an arm 118 which carries a pawl 119 (Fig. 2) adapted to engage ratchet teeth 120 for the purpose of retracting the block 116 near the end of a resetting operation to thereby release the shaft 72 for normal counting operations.

The lower counter units 13 and 13a are provided with clutch device 122 and brake device 123 which are of substantially the same construction as the clutch device 92 and brake device 110. The arms 102 and 124 of the two clutches 92 and 122 are interconnected by a link 125 whereby the clutches are adapted to be actuated simultaneously. A spring 126 is connected to the link 125 to bias the clutch arm 102 and 124 in a clockwise direction, as viewed in Figs. 1, 2 and 4.

The brake devices 110 and 123 are also arranged for simultaneous operation, the arms 118 and 129 being connected by a link 128, biased by a spring 130 in a clockwise direction, as viewed in Figs. 1, 2 and 4.

The predetermined order of actuating the links 125 and 128 is controlled by a cam disc 132 and a cam lug 134 carried by the reset shaft 85. The link 125 is provided with a roller 135 which engages the surface of the cam disc 132. The arm 129 of the device 123 is provided with a finger 136 which is adapted to be engaged by the lug 134.

The cyclic movement of the reset shaft 85 is controlled by a notched disc 140 (see Figs. 2, 4 and 6). Cooperating with the notches 141 and 142 of the disc 140 are zero stop pawl 143 and pullback limiting pawl 144. Pivotally mounted on the frame 10 adjacent the zero stop pawl 143 is a latch 145 biased by a spring 146 to engage a pin 147 on the zero stop pawl 143. Fig. 6 illustrates the position of zero stop pawl 143 in engagement with the notch 141 at the end of a resetting operation, the pawl operating to prevent continued movement of a shaft 85 in a clockwise direction. To initiate a new resetting operation the shaft 85 must first be rotated in a counterclockwise direction, as viewed in Figs. 4 and 6, until the pawl 144 engages the notch 142. This pullback movement operates to dislodge the pawl 143 from the notch 141. The resulting clockwise movement of the pawl 143 raises the pin 147 sufficiently for the shoulder 148 of the latch 145 to slide beneath the pin thereby retaining the pawl 143 free of the notch 141, a position shown in Figs. 2 and 4. After the reset shaft 85 has been rotated counterclockwise throughout the extent of a pullback movement, the shaft 85 may then be rotated in a clockwise direction through one and a fraction rotations until the latch 145 has been tripped by the pin 149 to permit the zero stop pawl 143 to enter notch 141 and terminate the resetting operation.

It will thus be understood that the zero resetting mechanism is first given a slight pullback movement to withdraw the zero stop pawl and then a forward movement during which the shafts 18 of the several counters are driven in a reverse direction to return the counting elements to zero position, the stop pawl being re-

leased for movement to stopping position near the end of the resetting operation.

A cyclic operation of the driving and resetting mechanism is described herebelow by setting forth the relative positioning of parts at certain points during a resetting operation to show how the clutch mechanism operates. The counter units 12 and 12a only are referred to in this description of operation for the sake of brevity.

(1) Fig. 1 illustrates the position of the resetting mechanism at the termination of a resetting operation. The clutch block 96 is in biased position, having been released from the pawl 105 position, to provide an effective driving connection between the shaft 72 and the clutch gear 75. The brake device 110 is in retracted position releasing the gear 114, whereby the shaft 72 is capable of being driven by a source of power such as a meter or the like.

(2) During the pullback movement of the reset shaft to the position indicated in Fig. 2, where pawl 144 engages the notch 142, the zero stop pawl is dislodged from the notch 141 and latched in raised position by latch 145. The right hand side of the latch 145 (Fig. 6) is engaged by the pin 149 during the pullback movement to urge the shoulder 143 of the latch beneath the lug 147 on the zero stop pawl 143. The pullback movement also causes the cam lug 134 to be withdrawn from the finger 136, thus permitting the spring 130 to move the arms 118 and 129 clockwise from the position indicated in Fig. 1 to that indicated in Fig. 2. The pawl 119 of the brake device 110 rides over the ratchet teeth of the block 116 during this movement. The roller 135 remains on the surface 150 of the cam 132 throughout the pullback movement, permitting the link 125 to remain in fixed position.

(3) Initial clockwise movement of the resetting shaft 85 causes the cam lug 134 to engage the finger 136 to actuate brake arms 118 and 129 in a counterclockwise direction, whereupon the pawl 119 rotates the block 116 to an extreme retracted position, that is, until the pawl 119 engages an abutment 151 (and pawl 152 of the brake device 123 engages an abutment 153), whereupon the ratchet teeth 120 are disengaged and the block 116 is released for rotation by spring 117 to gripping engagement with gear 114. The extreme or releasing position for the arms 118 and 129 is illustrated in Fig. 3. By this actuation of the device 110, the drive shaft 72 is held against movement during resetting of the counting elements.

(4) By continued movement of the reset shaft in a clockwise direction, the cam lug 134 is caused to disengage the finger 136 whereby the arms 118 and 129 assume the positions illustrated in Figs. 1 and 4 by action of spring 130. At about this point in the movement of the reset shaft, the inclined surface 155 of cam 132 engages the roller 135 to actuate the link 125, rotating the arms 102 and 124 counterclockwise. This movement of arm 102 causes the pawl 105 to engage the ratchet teeth 104, retracting the block 96 to release the gear 75. With the roller 135 raised to the cam surface 156, the reset mechanism is then in a position to initiate resetting movement of the counter shafts 18.

(5) Immediately following the movement of the roller 135 onto the surface 156, the mutilated gear 91 is adapted to engage the teeth of gear 82a. Continued rotation of the reset shaft causes the mutilated gear 91 to drive gear 82a to reset

counter 12a backwards to zero position, the resetting movement being transmitted from counter 12a to counter 12 through bevel gears 68a and 67, the shaft 62, and bevel gears 66 and 68. The resetting movement is transmitted to counters 13 and 13a by a similar driving mechanism.

(6) The mutilated gears disengage the gears of the counters just before the lip portion 158 of cam 132 engages the roller 135. The lip portion 158 is adapted to raise the roller 135 to move the arms 102 and 124 to their extreme raised position. (See Fig. 4.) Upon movement of arm 102 to this position, pawl 105 engages an abutment 160, releasing the clutch block 96 for movement by the spring 97 to clutch engaging relation with gear 75. The pawl 161 associated with arm 124 engages an abutment 162 at the same time pawl 105 engages abutment 160. When the lip 158 disengages the roller 135 the link 125 is caused to rotate clutch arms 102 and 124 clockwise by spring 126 to the position illustrated in Fig. 1.

(7) A continued rotation of the shaft 85 causes the cam lug 134 to engage the finger 136, rotating the arms 118 and 129 in a counterclockwise direction. This movement retracts the block 116 by engagement of pawl 119 with ratchet teeth 120, whereby the gear 114 is released, thus unlocking the drive shaft 72 for normal operation. The arms 118 and 129 are retained in retracting position, as shown in Fig. 1 by continued engagement of the cam lug 134 with finger 136. Just prior to the completion of the resetting movement, the pin 149 is adapted to engage and trip latch 145 to release the zero stop pawl 143 to terminate the resetting operation with the mechanism in the position illustrated in Fig. 1.

From the foregoing it will be clear that the counters 12, 12a and 13, 13a are reset to zero position by a movement which positions the clutch mechanism to hold the driving means against movement and release the counters for movement independent of the driving means. The mutilated gears pick up the drives to the several counter units to reset the numeral wheels backwards to zero position. After the shafts of the several counters have been rotated sufficiently to insure complete resetting of the numeral wheels, the mutilated gears become disengaged, the clutch devices actuated to reconnect the counters to the driving means and to release the locking hold upon the drive.

While I have shown only one form of clutch mechanism and but one application thereof, it is recognized that many modifications and other applications may be made without departing from my invention. The clutch and brake devices 92 and 110, for example, can be used singly instead of in the combination arrangement illustrated and the means for actuating the clutch devices can take entirely different forms from the actuating mechanism with which they are herein illustrated. It should therefore be understood that the construction herein illustrated and described is intended to be illustrative of the invention only and not as limiting the scope of the appended claims.

I claim:

1. A clutch mechanism comprising a shaft, means providing a friction surface fixed relative to said shaft, a member threadably mounted on said shaft for rotary movement relative to said shaft in directions toward and away from said friction surface, an element rotatably mounted on said shaft between said surface and said member, means for biasing said member for move-

ment toward said surface to hold said element against said surface, and means operative to retract said member to release said element.

2. A clutch mechanism comprising a shaft, means providing a friction surface fixed relative to said shaft, a member threadably mounted on said shaft for rotary movement relative to said friction surface, an element rotatably mounted between said surface and said member, means for biasing said member for movement toward said surface to hold said element against said surface, means operative to retract said member to release said element, and means operative upon a predetermined movement of said retracting means to release said member from said retracting means.

3. A clutch mechanism comprising a shaft, means providing a friction surface fixed relative to said shaft, a member threadably mounted on said shaft for rotary movement relative to said friction surface, an element rotatably mounted between said surface and said member, means biasing said member for movement toward said surface to hold said element against said surface, ratchet teeth carried by said member, means for retracting said member including a pawl engageable with said ratchet teeth, and means for disengaging said pawl from said ratchet teeth upon a predetermined movement of said retracting means.

4. A clutch mechanism comprising a shaft,

- a friction disc fixed relative to said shaft, a block threadably mounted on said shaft for rotary movement relative to said shaft in directions toward and away from said disc, an element rotatably mounted between said disc and said block, means biasing said block for movement toward said disc to clutch said element to said shaft, ratchet teeth carried by said block, an annular member rotatably mounted on said block, a pawl carried by said member adapted to engage said teeth, means for moving said member and pawl to retract said block and thereby release said element, and means operative upon a predetermined movement of said member to cause said pawl to disengage said teeth, whereby said block is permitted to reclutch said element.
5. A clutch and brake mechanism comprising a drive shaft, a gear fixed to said shaft, a gear adapted to be driven from said shaft, said driven gear being rotatably mounted on said shaft adjacent to said fixed gear, a member mounted on said shaft for movement relative to said shaft toward and away from said fixed gear to clutch said driven gear to and release said driven gear from said fixed gear, a third gear meshing with said fixed gear, brake means for holding said third gear against movement, and means for controlling said brake means and said member to first actuate said brake means to hold said drive shaft against movement and then to move said member to release said driven gear.

KENLY C. BUGG.
